COVER FASTENER

Filed July 3, 1922

INVENTOR
Thomas C. Wentworth
By
Deis Sprague,
Attorney

UNITED STATES PATENT OFFICE.

THOMAS C. WENTWORTH, OF CORNISH, MAINE.

COVER FASTENER.

Application filed July 3, 1922. Serial No. 572,628.

To all whom it may concern:

Be it known that I, THOMAS C. WENTWORTH, a citizen of the United States, residing at Cornish, county of York, State of Maine, have invented certain new and useful Improvements in Cover Fasteners, of which the following is a specification.

This invention relates to shipping cases and particularly to a cover fastener there-
10 for.

For the purposes of this application I shall show and describe my invention in its adaptation to an egg case of standard commercial type, although it will be understood
15 that such showing is purely illustrative and in no way limiting.

In a shipping case of this type the cover is a loose lid and it is accordingly desirable that the cover be securely fastened over the
20 top of the box by a fastening which will be capable of being set up tightly enough to bind the cover on the box without however displacing the cover laterally relative to the box top during the action of locking the
25 cover fastener. It is also desirable that the cover fastener itself shall serve as a hinge for the cover so that the cover may be swung back when the box is opened without complete disconnection from the box. An-
30 other requisite is that the cover fastener shall be capable of being easily locked and unlocked, and when locked shall be positively fastened so as not to accidentally become disengaged in shipment.

35 To the end therefore of providing a cover fastener embodying the foregoing features I have devised my present invention.

In it the cover fastener consists of one or more reinforcement strips, which are pref-
40 erably passed completely around and rigidly fastened to the bottom and sides of the box and terminate opposite the seat for the box cover and at their terminals carry a hinge member and a locking member which
45 are adapted to be detachably connected to each other to tighten the strip upon the box cover, and thereby lock the cover against movement upon the box.

The separable connection between the
50 terminals of the clamping strip consists of a pair of spaced fastener members which are slidably mounted upon the box cover for limited travel transversely thereof. One of said adjustable fastener members is perma-
55 nently engaged with the hinge member of

the clamping strip thereby hinging the cover to the box, and the other fastening member is adapted to be releasably engaged by the locking element at the opposite terminal of the clamping strip. When the fastener members are drawn towards each other by means of a suitable adjusting device, the clamping strip is drawn taut over the box cover and the cover is thereby permanently locked upon the box.

60 The construction and operation of my combination reinforcement and fastener is described and illustrated in the accompanying specification and drawings, and the characteristic features of novelty are particularly pointed out in the appended claims. 70 Throughout the specification and drawings like reference characters are correspondingly employed, and in the drawings:

Fig. 1 is an end view of a shipping case 75 equipped in accordance with my invention and indicating in dotted lines the cover raised.

Fig. 2 is a plan view thereof, and

Fig. 3 is an enlarged detail section partic- 80 ularly showing one of the cover fasteners.

I have indicated generally at 1 an egg case of standard type and at 2 the removable cover therefor.

85 My cover fastener consists of one or more clamping strips 3, here shown as two strips applied adjacent either end of the case, and permanently attached, as indicated at 4, to the sides and preferably also to the bottom of the box and each terminating adjacent 90 the seat for the box cover in loop 5, 5',

95 Mounted upon the upper face of the cover adjacent each end thereof for limited sliding travel transversely thereon and connected to the terminals 5 of the strip is a pair of spaced fastener blocks 6 and 7, which are adapted to be drawn together to tighten the strip 3 about the box and thereby clamp the cover over the box top. To this end, each block 6 carries a bolt 8 which is adapted 100 to be screwed into the block 7 to draw the blocks together.

In order to fix the blocks upon the cover and guide and limit their travel relative to each other, the top face of the cover is, as 105 here shown, provided with one or more longitudinally disposed anchoring strips 9, and each block is enclosed within a covering strip 10 which combines the function of a protective cover and an attaching means 110

for the blocks, and is passed beneath the anchoring strips 9 to slidably attach the blocks to the box cover.

The block 6 at its outer end is vertically notched as indicated at 11 and the protective strip 10 for said block has a hole let therethrough in registry with said notch so as to provide a catch within which a hook 12 looped through the adjacent closed end 10 5 of the binding strip 3 may be engaged. The catch thus provided is preferably reinforced by a reinforcing bar 13 which is set transversely across the outer end of the block 6 between the block and its covering strip. 15

The covering strip 10 at the outer end of the block 6 has a hole let therethrough within which the head 15 of the bolt is lodged between the inner end of the block 20 itself and its covering strip.

Between the inner end of the opposite block 7 and its covering strip is confined a threaded bearing piece 16 which is tapped and threaded to receive the threaded end of 25 the bolt 8 which is provided between its ends, with a wing nut 17 by means of which the bolt may be turned to draw the blocks toward each other. The top face of the cover 2 beneath the wing nuts is recessed as 30 indicated at 18 to permit the bolts to be conveniently grasped by the fingers in setting up the bolts.

The covering strip at the outer end of the block 7 is spaced therefrom sufficiently 35 to provide a loop 19 under which is engaged a loop 20 which is also connected to the looped end 5' of the binding strip 3 so as to afford a permanent hinged connection for the cover.

40 In assembling the elements of my invention the binding strips 3 are fastened to the sides and bottom wall of the box and the anchoring strips for the blocks 6 and 7 are attached to the cover. The blocks 7 are hinged by means of the loops 20 to the loop 45 ends 5' of the binding strips and the locking hooks 12 are engaged in the locking recesses 11 of the blocks 6. The cover 2 may then be fastened by drawing the blocks towards each other by means of the bolts 8 50 to tighten the strips 3 upon the cover. In such action, the blocks slide transversely of the cover in their guides 9 without however displacing the cover relative to the top of 55 the box.

When the strips 3 are released by disconnecting the hooks 12 from the blocks 6 and the box cover is opened, the loops 20 turn upon the loop ends 5' of the strips as pintles, 60 thereby limiting the opening movement of the cover and preventing complete disconnection of the cover from the box.

In its broadest conception, of course, the clamping strip 3 is to be considered as a pair 65 of anchoring elements rigidly fastened to

opposite sides of the box adjacent the seat for the box cover, and the fastener blocks 6 and 7 are to be regarded as an adjustable flexible connection between said anchoring elements, which, due to its nature of attachment to the box cover not only hinges the cover to the box, but also permits the clamp to be drawn taut and thereby lock the cover in position over the mouth of the box. In other words the fastener blocks 70 combine the functions of a hinge and an adjustable clamp for the box cover. 75

Various modifications in the form and construction of my invention may obviously be resorted to if within the limits of the 80 appended claims.

What I therefore claim and desire to secure by Letters Patent is:

1. A cover fastener for a shipping case, comprising a pair of anchoring portions 85 rigidly attached to the sides of the case adjacent the seat for the cover, and an adjustable clamping connection carried by the cover and hinged at one end to one of said anchoring portions to provide a hinge for 90 the cover and adapted to be detachably connected at its opposite end to the other anchoring portion, and means whereby said connection may be adjusted to clamp the cover upon its seat. 95

2. A cover fastener for a shipping case comprising a strip fastened to the sides of the case and terminating adjacent the seat for the cover, a clamping device adjustably mounted upon the cover and separably connecting the ends of said strip, said device being hinged to one terminal of said strip and hinging the cover to the shipping case and detachably connectible with the opposite terminal of the strip, and means whereby 100 said device may be adjusted to clamp the cover upon its seat. 105

3. A cover fastener for a shipping case, comprising a strip fastened to the sides of the shipping case, a pair of spaced clamping members adjustably mounted upon the cover and separably connecting the ends of said strip, and means whereby said members may be drawn together to clamp the cover upon 110 the shipping case. 115

4. A cover fastener for a shipping case, comprising a strip fastened to the sides of the shipping case, a pair of spaced clamping members adjustably mounted upon the cover and separably connecting the ends of said strip and means whereby said members may be drawn together to clamp the cover upon 120 the shipping case, one of said members hinged to said strip to provide a hinge connection between the cover and the shipping case. 125

5. A combination reinforcement and fastener for the cover of a shipping case comprising a clamping strip secured to the case and terminating adjacent the seat for the 130

cover, a hinge member engaged with one terminal of the clamping strip and a locking member engaged with the opposite terminal of said strip, a pair of spaced fastener members mounted for limited sliding travel towards each other on the case cover, one of said fastener members adapted for locking engagement with said locking member and the opposite fastener member connected with 5 said hinge member and means whereby said fastener members may be drawn towards each other to tighten the clamping strip and bind the cover upon the shipping case.

6. A combination reinforcement and fastener for the cover of a shipping case comprising a clamping strip secured to the case and terminating adjacent the seat for the cover in a pair of closed loops, a hinge member engaged with said closed loop at one 10 end of the clamping strip and a locking member engaged with the loop at the opposite end of said strip, a pair of spaced fastener members mounted for limited sliding travel towards each other transversely of 15 the case cover, one of said fastener members having a locking recess within which said locking member is adapted to engage and the other fastener member connected with said hinge member, and means whereby 20 said fastener members may be drawn towards each other to tighten the clamping strip and bind the cover upon the shipping case.

7. A combination reinforcement and fastener for the cover of a shipping case comprising a clamping strip passed around the sides and bottom of the shipping case and anchored thereto and terminating adjacent 25 the seat for the cover, a hinged loop engaged with one terminal of the clamping strip and a locking hook engaged with the opposite terminal of said strip, a pair of spaced fastener blocks mounted for limited sliding travel towards each other on the case cover, one of said blocks adapted for engagement 30 with said locking hook and the other block connected with said hinge loop, and means whereby said blocks may be drawn towards each other to tighten the clamping strip and bind the cover upon the shipping case. 35

with one terminal of the clamping strip 40 and a locking hook engaged with the opposite terminal of said strip, a pair of spaced fastener blocks mounted for limited sliding travel towards each other on the case cover, one of said blocks adapted for engagement 45 with said locking hook and the other block connected with said hinge loop, and means whereby said blocks may be drawn towards each other to tighten the clamping strip and bind the cover upon the shipping case. 50

8. A combination reinforcement and fastener for the cover of a shipping case comprising a clamping strip passed around the sides and bottom of the shipping case and anchored thereto and terminating at the 55 seat for the cover, a hinged loop engaged with one terminal of the clamping strip and a locking hook engaged with the opposite terminal of said strip, a pair of spaced fastener blocks mounted for limited sliding 60 travel towards each other on the case cover, one of said blocks having a locking recess within which said locking hook is adapted to be engaged and the other block connected with said hinge, strips covering said 65 blocks, anchoring elements mounted upon the case cover and under which said covering strips are slidably engaged, and means whereby said blocks may be drawn towards each other to tighten the clamping strip and 70 bind the cover upon the shipping case.

In testimony whereof I affix my signature in presence of two witnesses.

THOMAS C. WENTWORTH.
